UNITED STATES PATENT OFFICE.

ERASTUS E. WINKLEY, OF LYNN, MASSACHUSETTS, ASSIGNOR TO UNITED SHOE MACHINERY COMPANY, OF PATERSON, NEW JERSEY, A CORPORATION OF NEW JERSEY.

LEVELING-MACHINE.

1,238,866.

Specification of Letters Patent. Patented Sept. 4, 1917.

Application filed May 8, 1916. Serial No. 96,076.

To all whom it may concern:

Be it known that I, ERASTUS E. WINKLEY, a citizen of the United States, residing at Lynn, in the county of Essex and State of Massachusetts, have invented certain new and useful Improvements in Leveling-Machines; and I do hereby declare the following to be a full, clear, and exact description of the invention, such as will enable others skilled in the art to which it appertains to make and use the same.

The present invention relates to sole leveling machines and more particularly to machines of this type provided with a shoe supporting jack and a coöperating leveling roll which are moved relative to one another to cause the roll to traverse lengthwise of the shoe sole.

In certain styles of shoes the ball portion of the sole is separated from the shank by a well-defined ball line which may consist of a single straight or curved line extending entirely across the sole, or of a broken line consisting of two straight or curved lines extending from the opposite margins of the sole and meeting in the central portion of the sole.

The object of the present invention is to provide a leveling machine embodying a shoe supporting jack and coöperating leveling roll which has an improved mode of operation to enable the shoe soles above described to be properly leveled without destroying or obliterating the ball line.

With this object in view, a feature of the invention consists in the provision, in a machine of this type having a leveling roll, of mechanism for inclining the roll relative to the direction of travel of the roll lengthwise of the shoe to position the axis of the roll substantially parallel with that portion of the ball line which is engaged by the roll as it passes thereover.

Still further features of the invention consist in certain novel features of construction, combinations, and arrangements of parts hereinafter described and claimed, the advantages of which will be obvious to those skilled in the art from the following description.

In the accompanying drawings illustrating the preferred form of the invention, Figure 1 represents a side elevation of a leveling machine embodying the present invention; Fig. 2 is a detail illustrating a par-

tial top plan view of the machine and showing the mechanism for supporting and actuating the leveling roll; Fig. 3 is a detail showing a side elevation, partly in section, of a portion of the mechanism for inclining the roll; and Fig. 4 is a view illustrating the position of the roll with the axis parallel to the ball line, when passing over the ball line at one side of the shoe sole.

The present invention is conveniently embodied in a leveling machine of the type shown and described in the patent to Winkley No. 555,548, dated March 3, 1896. This machine comprises a frame 1 having a shoe supporting jack 2 fulcrumed at 3 and oscillated through the usual mechanism comprising a depending arm 5, connecting rod 6, and rotary cam mounted upon the cam shaft 7. The shoe sole is leveled by a roll 10 which is supported in a roll carrying head 11 swiveled in a bed 12 fulcrumed upon the upper part of the machine frame at 13. The leveling roll is slidingly supported in ways formed in opposite sides of the roll carrying head 11 and is vibrated during the operation of the machine through a link 15 passing through the roll carrying bed and operated by the usual actuating mechanism, not shown. With this construction the relative longitudinal position of the roll and jack are changed by the oscillatory movement of the jack and the relative lateral inclination of the roll and jack are varied through the swiveling movements of the head upon the roll carrying bed. The machine is of the usual twin type having a pair of shoe supporting jacks and coöperating rolls and in the drawings only so much of the twin machine is shown as applies to the present invention.

It is desirable that shoe soles in which the ball line is characterized by a sharp break in the sole shall be leveled upon machines embodying a leveling roll. To this end, mechanism is provided for inclining the roll relative to the direction of travel lengthwise of the shoe sole to position the roll with the axis of rotation substantially parallel to that portion of the ball line engaged by the roll when passing thereover. In the illustrated embodiment of the invention the roll is shown as operating upon a sole having what is known as a "cottage shank" in which the median line of the shank is denoted by a sharp ridge extending

lengthwise of the shank and the ball line is denoted by two intersecting straight lines inclined to one another to form a V having its apex at the junction of the ball line and median line of the shank. In the present type of machine the leveling roll is caused to traverse lengthwise of the sole and to bear successively upon opposite sides of the sole. In order to position the leveling roll with the axis parallel to the respective portion of the ball line with which the roll engages, the roll is gradually inclined when passing down one side of the shoe sole from the toe until it assumes a position in which the axis is parallel to the ball line on that side of the sole. This position is maintained during the time that the leveling roll is traversing back and forth over the ball line, and as the roll is returned toward the toe, it is gradually straightened. When passing down the opposite side of the shoe sole the roll is inclined in the opposite direction until it assumes a position with the axis substantially parallel to the ball line upon that side of the shoe sole. According to this mode of operation the shoe sole is properly leveled throughout all portions of its length without obliterating the ball line or destroying the characteristic appearance.

The leveling roll 10 is supported at its opposite ends upon slides 20 and 21, respectively connected by a yoke 19 and slidably supported in slideways formed in opposite sides of the roll carrying head 11 to permit the usual vibratory movement of the leveling roll. The slides are connected to the vibrating member 15 through a transverse lever 22 fulcrumed midway between its ends upon a vertical stud 23, projecting from a head 24 secured to the end of the member 15, as shown clearly in Fig. 3. The slides 20 and 21 are connected, respectively, to opposite ends of the lever 22 through links 25 and 26. This construction serves as a connection for causing the vibratory movement of the member 15 to be imparted to the leveling roll. In order to position the roll with the axis of rotation inclined to the direction of travel, the slides 20 and 21 are provided with curved faces and are moved relative to one another in the slideways through the links 25 and 26. To this end, mechanism is provided for controlling the position of the slides by an angular movement of the lever 22. The lever 22 is provided with an arm 30 extending therefrom to form a 3-arm bell-crank, as shown clearly in the drawings. The arm 30 is operatively connected with a head 32 slidably supported upon a transverse guide rod 33 secured at its opposite ends in the roll carrying head 11. The head 32 is provided with a guideway 35 in the under face which receives a guide roll 36 journaled upon the free end 65 of the arm 30 to permit reciprocating move-

ments of the arm relative to the head, while causing transverse movements of the head to be imparted to the arm 30 and lever 22. The head 32 is adjusted transversely to incline the leveling roll through a bell-crank lever fulcrumed upon a stud 38 mounted in the upper portion of the head 11 and having one arm 39 operatively connected with the head 32, and a second arm 40 connected with the slide rod 42. The rod 42 is slidably supported in bearings 43, and is connected at its opposite end to a collar 45 slidably supported upon a cylindrical portion 46 of the roll carrying bed 12. The proper operative movements are imparted to the collar 45 through a bell-crank lever 48 fulcrumed upon the machine frame at 50 and having one arm 51 operatively connected with a peripheral groove 53 formed in the collar and a second arm 55 connected to an operating rod 56. The rod 56 is controlled by an actuating arm 58 fulcrumed at its lower end upon a shaft 59 and having its upper end operatively connected with a rotary path cam, indicated at 60, and mounted upon the cam shaft 7. In order to vary the angular movements imparted to the roll through the path cam, the rod 56 is adjustably connected with the arm 58 through a curved slide 62 projecting laterally from the lower end of the actuating arm 58 and having a slot 64 formed therein which receives an adjustable slide block 65 connected to the rod 56 and serving in the usual manner to adjust the end of the rod with relation to the slide. It will be noted from an inspection of Fig. 2 that the bell-crank 48 is provided with two arms 51, connected to form a yoke and each having a roll-engaging in a groove 53 formed in a collar 45 sliding upon the respective roll carrying bed. With this construction the actuating mechanism serves to incline both rolls simultaneously and in opposite directions to cause the rolls to respectively operate upon right and left shoes.

With the above construction the roll is initially positioned with its axis substantially at right angles to the direction of movement over the shoe sole, and as the roll progresses down one side of the shoe sole, it is gradually inclined until the axis of the roll is substantially parallel with that portion of the ball line which is engaged by the roll when passing from the ball portion of the shoe to the shank. This position of the roll is maintained while operating upon that side of the shoe and when approaching the toe at the completion of the leveling operation upon one side of the sole the roll is gradually straightened after which the preceding cycle of operations is repeated upon the opposite side of the sole.

While it is preferred to employ the specific construction and arrangement of parts shown

and described, it will be understood that this construction and arrangement is not essential except so far as specified in the claims, and may be changed or modified 5 without departing from the broader features of the invention.

The invention having been described, what is claimed is:

1. A sole leveling machine, having, in combination, a leveling roll, a shoe supporting jack, means for changing the relative longitudinal position of the roll and jack, and mechanism for automatically inclining the roll relative to the direction of travel 10 constructed and arranged to position the roll with the axis of rotation substantially parallel to the ball line when the roll passes thereover.
2. A sole leveling machine, having, in combination, a leveling roll, a shoe supporting jack, means for changing the relative longitudinal position of the roll and jack, and mechanism for automatically inclining the roll relative to the direction of travel 15 during the continued movement of the roll lengthwise of the shoe sole constructed and arranged to position the roll with the axis parallel to the ball line when the roll passes thereover.
3. A sole leveling machine, having, in combination, a leveling roll, a shoe supporting jack, mechanism for changing the relative longitudinal position and lateral inclination of the roll and jack, and mechanism 20 for automatically inclining the roll in opposite directions relative to the direction of travel when operating upon opposite sides of a shoe sole constructed and arranged to position the roll with the axis substantially 25 parallel to that portion of the ball line engaged by the roll as it passes thereover.
4. A sole leveling machine, having, in combination, a leveling roll, a shoe supporting jack, means for changing the relative longitudinal position of the roll and jack, a 30 rotary cam, and operative connections between the cam and roll for automatically in-

clining the roll relative to the direction of travel to position the roll with the axis substantially parallel with the ball line when 50 the roll passes thereover.

5. A sole leveling machine, having, in combination, a leveling roll, a shoe supporting jack, means for oscillating the jack, a roll carrying head, means for reciprocating the roll in the head, and mechanism for automatically inclining the roll relative to the head constructed and arranged to position the roll with the axis parallel to the ball line of the shoe when passing thereover. 55

6. A sole leveling machine, comprising a roll carrying head, a leveling roll slidingly supported in the head, mechanism for reciprocating the roll, a bellcrank lever fulcrumed upon the head, connections between the bellcrank lever and opposite ends of the roll to incline the roll relative to the direction of movement in the head, and mechanism for actuating the bellcrank lever to vary the inclination of the roll relative to the direction of travel. 60

7. A sole leveling machine, having, in combination, a leveling roll, a shoe supporting jack, means for varying the relative longitudinal position and lateral inclination 70 of the roll and jack, a roll supporting head, means for vibrating the roll in the head, and mechanism for automatically inclining the roll relative to the direction of travel during the relative longitudinal movement of the 75 roll and jack.

8. A sole leveling machine, comprising a roll carrying head, a yoke slidingly supported at opposite ends in the head, a roll journaled in the yoke, a lever fulcrumed 80 upon the head, connections between opposite ends of the lever and the yoke, means for reciprocating the lever, a bellcrank lever fulcrumed upon the head, and connections between the bellcrank and lever for moving the lever angularly to incline the roll relative to the direction of movement in the head. 85
